UNITED STATES PATENT OFFICE.

HENRY J. HAUSER, OF ROCHESTER, NEW YORK.

FOLDING DOLL-CRADLE.

1,368,145.

Specification of Letters Patent.

Patented Feb. 8, 1921.

Application filed May 3, 1920. Serial No. 378,444.

To all whom it may concern:

Be it known that I, HENRY J. HAUSER, a citizen of the United States, residing at Rochester, in the county of Monroe and 5 State of New York, have invented certain new and useful Improvements in Folding Doll-Cradles, of which the following is a specification.

This invention relates to cradles, and especially to toy cradles suitable for dolls, although it is capable of being made in larger size for infants.

The object of the invention is to provide an improved folding cradle which can be 15 cheaply constructed, and which can be set up for use in a manner to be hereinafter described. The device also includes a pillow frame or support which will be found useful in connection with the article.

20 The invention is illustrated in the accompanying drawings in which Figure 1 is a top plan of the cradle. Fig. 2 is a side elevation thereof. Fig. 3 is an end elevation. Fig. 4 is an edge view of the cradle folded. Fig. 5 is a plan of the cradle folded.

The bottom of the cradle comprises two boards or sections A which are hinged together at the middle as indicated at G. Each of the ends consists of a piece of strap metal 30 bent to form a head frame B and a rocker C, each frame consisting conveniently of a single piece of metal. These frames are pivoted to the outer ends of the bottom boards by means of hinge leaves H and a crank rod J which is welded or otherwise fixed at its ends to the adjacent sides of the end frame B. The crank I in the rod J is engaged by a flat spring catch E so that when the end piece is swung up the crank will be 40 caught by the catch, to hold the end in upright position, and when the end piece is swung down the catch will bear on the crank and hold the end piece in folded position, as shown in dotted lines in Fig. 4.

45 D is a bent wire pillow frame, the ends of which are pivoted at O to the head frames, and the cross bar of which will stop against a pair of stops F fixed to the bottom board, when the cradle is set up, the frame D extending at an inclination. This frame will be covered by a cloth indicated in dotted lines at N, to form a pillow. Q is a cord which extends around the top of the cradle, being run through holes R in the end frames, and 50 this cord will be drawn taut when the cradle is unfolded and set up. The frame so con-

structed may be covered by side cloths indicated in dotted lines at L, and by end cloths indicated in dotted lines at M, the former being hung on the cords Q and the latter being attached to the end frames by cords in the holes R. These coverings may or may not be used, but will preferably be used to provide an inclosure and give a neat appearance.

55 To fold the cradle the pillow frames D are lifted or disengaged from the stops F and the end frames B are snapped down inwardly, folding against the bottom A. The hinge G is then "broken" upwardly or inwardly and the bottom boards A will fold together against each other as shown in Fig. 4. The frame may be set up by unfolding the bottom, and opening out the end frames until the cranks I are engaged by the catches 70 E and the pillow frames are engaged against the stops F.

60 The device can be quickly folded or unfolded by a child and can be easily carried or stored in a small space.

65 The sides being made of cloth and cords will fold in between the parts of the frame.

70 Instead of being made of cloth the sides can be made of any other flexible material, and this material can either be tacked to the bottom board or fastened in place by cords similar to the cords Q. The bottom A can be made of wooden boards or can be made of any other suitable material such as metal or fiber.

75 I claim:

1. A folding cradle comprising a bottom, a head and rocker frame at each end thereof, a cranked rod extending between opposite sides of each frame and pivotally connected 95 to the bottom, and a spring catch fixed to the bottom and engaging the crank of each rod to hold the frame at adjustment.

2. A folding cradle comprising bottom sections hinged together at the middle, an 100 end head and rocker frame pivoted to the outer end of each section, and a catch between each section and one of the frames, to hold the latter in adjusted position, and flexible side members connecting the end frames 105 above the bottom sections.

90 In testimony whereof, I affix my signature in presence of two witnesses.

HENRY J. HAUSER.

Witnesses:

ARTHUR B. NORRIS,
RAYMOND H. ARNOT.
